FINGER RING BOX

Nicholas Barbieri, Providence, R. I., assignor to Uncas Manufacturing Company, a corporation of Rhode Island

Application January 20, 1956, Serial No. 39,866

Term of patent 14 years

(Cl. D80—5)

Fig. 1.

Fig. 2.

Fig. 3.

Fig. 4.

Fig. 1 is a top view of a finger ring box, showing my new design;

Fig. 2 is a side view thereof;

Fig. 3 is a sectional view taken on lines 3—3 of Fig. 1; and

Fig. 4 is a perspective view of the box in open position.

I claim:

The ornamental design for a finger ring box, substantially as shown.
